UNITED STATES PATENT OFFICE.

JACOB VAN DER VORN, OF MILWAUKEE, WISCONSIN, ASSIGNOR TO EXPANDEM TOOL
AND MANUFACTURING COMPANY, A CORPORATION OF ILLINOIS.

BORING-BAR.

1,232,411.

Specification of Letters Patent. Patented July 3, 1917.

Application filed April 9, 1917. Serial No. 160,697.

To all whom it may concern:

Be it known that I, JACOB VAN DER VORN, a citizen of the United States, and resident of Milwaukee, in the county of Milwaukee, and State of Wisconsin, have invented new and useful Improvements in Boring-Bars, of which the following is a description, reference being had to the accompanying drawings, which are a part of this specification.

10 The invention relates to boring bars.

The invention is designed more particularly to provide means whereby the boring tools or cutters may be held in the boring bar and adjusted for use as required.

15 In devices of this character, simplicity, accuracy, ease of operation and fewness of parts are prime requisites and the present invention has been designed to satisfy these requisites only three working parts besides

20 the tools being used thus reducing the chance in inaccuracies of construction which would necessarily result as the number of parts is increased and also reducing the cost of manufacture and producing a device simple in operation.

25 The invention further consists in the several features hereinafter set forth and more particularly defined by claims at the conclusion hereof.

30 In the drawings:

Figure 1 is an elevation view of the device embodying the invention;

Fig. 2 is a section taken on the line 2—2 of Fig. 1;

35 Fig. 3 is a section taken on the line 3—3 of Fig. 2;

Fig. 4 is a section taken on the line 4—4 of Fig. 1.

In the drawings the numeral 5 designates
40 the working end portion of the cylindrical
boring bar which has a diametrically ex-
tending cylindrical bore or aperture 6, a
longitudinally extending slot 7 communicat-
ing at its upper end with the aperture 6
45 and in line therewith but of less width than
the diameter of the aperture 6, a cylindrical
aperture 8 at right angles to the aperture 6
and leading from one side into said aper-
ture, a threaded bore 9 at right angles to
50 the slot 7 and communicating with the lower
end thereof and having a smaller bearing
aperture 10 communicating with its bottom
11 and coaxial with said aperture 9.

Disposed within the bore 6 is a right and
55 left hand threaded tool-feeding and ad-

justing screw 12 having a reduced central
portion 13 forming a groove to receive a
projection 14 extending from a plug or block
15 tightly fitted into the aperture 8 where-
60 by the screw 12 is free to rotate in the bore
6 but is prevented from moving laterally.
The screw 12 is provided with a square re-
cess 12' for receiving the end of a key to
turn it.

Disposed within the lower portion of the
slot 7 is a clamping block 16 having a
finished tool engaging surface 17 and a
slightly tapered centrally disposed notch 18.

Interposed between the screw 12 and the
block 16 are the tools 19 having accurately
70 finished threads or worm racks 20 adapted
to directly and respectively engage with the
right and left hand screw member and hav-
ing finished plain surfaces 20' adapted to
engage the surface 17 of the block 16. 75

The block 16 is held in clamping engage-
ment with the tools and the tools thereby
clamped between the screw 12 and said block
by means of a screw 21 having a threaded
portion 22 in threaded engagement with
80 bore 9, a tapered portion 23 in engagement
with the notch 18 in the block 16 and a
straight cylindrical portion 24 having its
bearing in the aperture 10, said screw 21
also having a square recess 25 therein for
85 receiving a key to turn the screw into the bar
and thereby wedge the tapered portion 23
against the block 16 thus moving said block
against the tools which are consequently
90 tightly held against the adjusting screw 12
and thus locked in position.

With the construction above described to
adjust the tools it is only necessary to insert
the key and loosen the screw 21 slightly and
then by inserting the key in the recess 12'
95 and turning the screw 12 in the desired di-
rection the tools 19 may be moved inwardly
or outwardly as desired and be locked in
place by screwing in the screw 21 against
the block 16. 100

In devices of this character the boring
bar usually carries several tools to make
the roughening and the finished cuts and it
will be noted that the construction hereto-
fore described is such as to be used at any
105 place along the bar and that the clamping
means is located in back of the clamping
block.

It will be noted that the adjusting screw
is directly in contact with the tools at all 110

times and that by making an accurate fit between these parts the chance for error is much less than in those devices of this type which use a block or blocks interposed between the adjusting screw and the tools and also that the entire portion of the tool held within the bar has its bearing upon the adjusting screw and the clamping block thus assuring a tight fit between the parts to 10 resist strain.

It will be noted that due to the arrangement and fewness of parts that the operation is simple, the device inexpensive and capable of accurate work.

15 15 What I claim as my invention is:

1. In a boring tool, the combination of a bar, a right and left hand threaded adjusting screw mounted within the bar, a clamping block within the bar, a pair of cutting tools carried by the bar, each having a threaded edge in direct engagement with the screw and their other opposite edge in direct engagement with the block, and means for clamping the tools between the screw 20 and the block.

2. In a boring tool, the combination of

a bar, a right and left hand threaded adjusting screw mounted within the bar, a clamping block within the bar, cutting tools carried by the bar, each having a threaded edge in direct engagement with the screw and their opposite edge in direct engagement with the block, and a locking screw wedgingly engaging the block to clamp the tools between the adjusting screw and said block.

3. In a boring tool, the combination of a bar, a right and left hand threaded adjusting screw mounted within the bar, a clamping block mounted within the bar and provided with a notch, a pair of cutting tools disposed between and in direct engagement with said screw and clamping block and provided with threads so as to be moved on the rotation of said screw, and a locking screw within the bar having a tapered portion engaging in the notch of said clamping block to clamp the tools between the adjusting screw and said block.

40 45 50 In testimony whereof I affix my signature.

JACOB VAN DER VORN.
